WOOD-PRESERVING APPARATUS

Grant B. Shipley, Pittsburgh, Pa.

Application October 20, 1942, Serial No. 462,742

1 Claim. (Cl. 21—63)

This invention relates to the impregnation of wood with preservatives to make it resistant to decay, insects, etc., and more particularly to a method and apparatus for carrying out the treatment more safely than heretofore.

In order to increase the life of forest products by preventing decay and destruction by insects, it is common practice to impregnate the wood with a preservative such as creosote distillate, creosote coal-tar solution, and creosote-petroleum mixtures. Several different methods are used for forcing the preservative into the wood, the most favored being the Rueping empty-cell treatment. In this method where air-seasoned timber is being treated, the air pressure in the treating cylinder is raised to suit the condition and species of wood being treated. For instance, in treating pine the air pressure may be raised to 100 pounds, but with oak and hardwood 60 pounds is sufficient. The treating cylinder is then filled with preservative, and without lowering the air pressure, the preservative is forced into the wood by either a pressure pump which forces additional preservative into the cylinder, or by air pressure on top of the preservative in the scale tank or pressure measuring tank connected to the treating cylinder. When the preservative pressure period is finished, the preservative is removed from the treating cylinder and a vacuum is applied to remove the free preservative remaining on the exterior of the wood to prevent dripping. The preservative is heated in the cylinder and tank connected to it.

The initial compressed air on the timber in the cylinder helps to open up the cells in the wood and also acts as a vehicle for carrying the preservative into the cells. When the preservative pressure period is finished, the air in these cells expands and forces the surplus preservative out of them, leaving the wood fibers impregnated with preservative. This is often called "kick-back." For instance, in the treatment of pine, 12 pounds of preservative may be forced into each cubic foot of the wood, but the kick-back may leave only about 6 pounds. With this procedure, deep and thorough penetration can be obtained with a minimum of preservative.

When green timber is being treated, the wood first is conditioned to remove resin, juices, and sap, and to soften the wood fibers. Thus, pine timber is usually conditioned in the treating cylinder under a steam pressure of 20 pounds gauge, whereas fir and oak are completely immersed in a hot preservative oil and then the temperature is gradually increased above the

boiling point of water while the treating cylinder is under vacuum.

The treating cylinders and other closed pressure vessels used in connection with wood preserving processes are usually equipped with steam heating coils for the purpose of heating the preservative to the desired temperature. Often, free carbon, wood chips, bark and dirt accumulate in the bottom of these treating vessels around the steam coils, with the result that when these coils are not covered with preservative the carbon may become incandescent and glow and set fire to the chips and bark, or sparks from the tram car wheels and other equipment entering the treating cylinder may cause a fire. There is also a possibility of static electricity causing fires and explosions. In the heating of preservative oils, the gases which are formed in the treating cylinder or in any other closed vessel where air is being used present a hazard, depending upon the flash point of the various preservative solutions and the temperatures involved due to the necessary heating of the preservatives. Furthermore, the air from the compressor may sometimes be contaminated with poor lubricating oil, and it is known that in such cases serious explosions have occurred in the compressor, pipes, and air receiver. Fires at wood-preserving plants are particularly disastrous and hard to control because of the great stocks of timber and highly inflammable preservative solutions.

It is among the objects of this invention to provide a method and apparatus for treating wood in which the danger of fires and explosions in the treating cylinder and other containers is greatly diminished, and in which this result is accomplished in a simple and inexpensive manner.

To accomplish the foregoing objects inert gases are substituted for air for purging the treating cylinder and other vessels during the cycle of operation and for putting pressure on the timber and preservative. Although a manufactured inert gas may be used, it is preferred to employ waste gas from the stack of the boiler that is a part of the preserving plant. To secure the proper inert gas from boiler stacks, complete combustion of fuel should take place in the boilers. In order to avoid the possibility of sparks and hot cinders entering the system, the inert gas preferably is withdrawn from the stack by a steam ejector which then forces the gas into the treating cylinder or other vessels as desired. The steam will destroy any live sparks and hot cinders and at the same time it will help purge the containers and eliminate the possibility of any free

carbon incandescence. The live steam helps to purify the gas, and the water used as a spray in the gas scrubber and cooler through which the gas is forced removes objectionable elements and cools the inert gas before it goes to the compressor or treating cylinder or other vessels. This same ejector can be arranged so that it will also create a vacuum in the treating cylinder, etc., as needed. The compressor is used to deliver the inert gas to a receiver at such increased pressures as may be required in carrying on the various cycles of operation used in the treatment of timber.

The preferred embodiment of the invention is illustrated in the accompanying drawing in which the single figure is a diagrammatic view of a wood preserving plant with one end of the treating cylinder open to show the wood being treated.

Referring to the drawing, the wood 1 to be treated is piled on a tram car 2 and rolled on tracks 3 into a treating cylinder 4 which is then closed. The next step, when the empty-cell method is practiced as illustrated here, is to create a gas pressure in the cylinder to open up the interstices of the wood. In accordance with this invention this pressure is created by forcing into the treating cylinder an inert gas. Preferably this gas is flue gas obtained from the stack 6 of the boiler plant 7 that forms a part of every wood preserving plant. To produce a proper inert gas, complete combustion of the boiler plant fuel should take place. Therefore, the boiler should be equipped with the necessary instruments and apparatus for the efficient use of fuel, and this will also result in more economical operation of the boiler.

In order to remove the gas from the boiler stack and force it into the cylinder, an ejector 8 is used which preferably is operated by dry steam supplied from pipe 9 at a pressure of about 125 to 150 pounds. The gas inlet of the ejector is connected to the boiler stack by a pipe 11, and the outlet of the ejector is connected by a pipe 12 to the top of cylinder 4. However, before the gas reaches the cylinder it preferably is diverted through a scrubber 13 and cooler 14 that are connected by pipes 16 and 17, respectively, to pipe 12 at points separated by a normally closed valve 18. Some, and at times all, of the scrubbed and cooled gas may be diverted from pipe 17 through a pipe 20 to a pipe 21 connecting stack pipe 11 with the inlet of a compressor 22. The outlet of the compressor is connected by a pipe 23 to a high pressure receiving tank 24 which in turn is connected by pipes 25, 26, and 27 to pipe 12 from the ejector.

Assuming, for the purpose of shortening this description, that all valves are closed at the beginning of each step of the process and are closed again immediately after the completion of each step, inert gas is drawn from the boiler stack by the ejector and may be delivered directly to the treating cylinder by opening valves 30, 31, 32, 33, and 34 in pipe 11 and valves 35, 36, and 37 in pipe 12. Or, valve 18 may remain closed and valves 38, 39, and 40 in pipe 16, and valve 41 in pipe 11, opened so that the gas will be scrubbed and cooled before reaching the cylinder. A large volume of inert gas is thus introduced into the cylinder, and the steam mixed with it helps wash and scrub the gas and to eliminate any sparks and hot cinders. Also, the steam helps purge the cylinder of explosive gases and destroys the incandescence of any free carbon that may occur as a result of the steam heating coil 42 in the

bottom of the cylinder. By first connecting the ejector directly to the treating cylinder the capacity of the compressor need be only about half of what it would have to be in case there were no ejector.

If a higher gas pressure in the treating cylinder is now desired, valve 36 is closed and valve 44 in pipe 20, valve 45 in pipe 21, valve 46 in pipe 23, valve 47 in pipe 25, and valve 48 in pipe 27 are opened. This connects the ejector with the compressor and the latter with the treating cylinder. On the other hand, the compressor may be connected directly to the boiler stack by opening valves 49 and 50 in pipe 21, or it can be connected to an auxiliary source of inert gas, an inert gas producer 51, by opening only valve 50.

After the gas pressure within the treating cylinder has been raised the desired amount, the cylinder is filled by gravity with a suitable liquid preservative from tank 55 by opening valves 56 and 57 in pipes 58 and 59, respectively, that connect the bottom of the tank with the bottom of the cylinder. Pipe 58 also leads to the bottom of a pressure measuring tank 60 filled with preservative. Valves 37 and 48, and a valve 62 in a pipe 63 connecting pipe 26 with the top of tank 55, are opened to allow the compressed gas in the cylinder to move up into the tank as the cylinder is filled with preservative. Thus the preservative and compressed inert gas change places and the gas pressure is maintained.

To force the preservative into the wood, pressure measuring tank 60 is connected to the bottom of the cylinder by opening valve 65 in pipe 58, and valve 57 in pipe 59. The preservative in this tank is forced into the cylinder by high pressure inert gas from the receiver 24 to which it is connected by pipe 66, containing valve 67, and pipes 25 and 26. After the preservative in the cylinder has been under pressure the necessary length of time, tank 55 is vented to blow off all gas to atmosphere by opening valve 62 and a valve 68 in a pipe 69 connecting pipe 26 with a vent pipe 70 connected to pipe 16. Valves 56 and 57 are then opened so that the pressure in the treating cylinder will force nearly all of the unused preservative therein up into tank 55. The high pressure gas on the preservative in the pressure measuring tank 60 is then fed into the top of the treating cylinder by opening valves 67, 43, and 37 which will generally force the balance of the preservative up into tank 55. However, if additional pressure is required, it can be taken from the receiver by opening valve 47. After the treating cylinder has been emptied of all preservative it is vented to atmosphere by opening valves 31, 48, and 68.

To avoid waste and drippage of preservative after the pressure period is finished, and to help dry the treated timber, a quick final vacuum in the treating cylinder is created by drawing a vacuum of about 15 inches on the cylinder by means of the ejector to release the hot heavy vapors. This is done by opening valves 72 and 73 in a pipe 74 connecting pipe 12 with pipe 11, and also opening valves 34, 35, and 38 and a valve 75 in vent pipe 70. Then when the heavy vapors have been released from the treating cylinder, a vacuum pump 71, connected through a pipe 78, a condenser 79, a pipe 80 and a valve 81 with pipe 74, is started to raise the vacuum to 24 inches or whatever may be desired. The condensate collects in the condenser and the vapors are discharged to atmosphere through a pipe 82.

When the foregoing operating cycle has been finished, it is necessary to determine the net quantity of preservative retained by the wood, and since before treatment the tank 55 was completely full and a known quantity of preservative was contained in the pressure measuring tank, the treating cylinder is drained into the pressure measuring tank by opening valves 57 and 65. With gas pressure from receiver 24 on top of the preservative in the measuring tank the preservative is forced up into tank 55 by opening valves 65 and 56. With the treating cylinder now emptied and tank 55 filled as at the start, the measuring tank is ready for the final measurement. The quantity of preservative remaining in the tank, when deducted from the initial amount, gives the net quantity of preservative retained by the wood. The measuring tank may then be filled with preservative from the working and storage tank 85 which is connected to the measuring tank through a general service pump 86 and a pipe 87 and pipe 58.

To facilitate deep and thorough penetration of the preservative in the wood by pressure processes, the timber should be seasoned and nearly dry, preferably air seasoned. Air seasoning is not always practicable, so, as a substitute, steaming of pine and boiling of fir and oak in the preservative under vacuum will help remove the resin, juices, sap, and water and softens the wood fibers. In steaming timber, live steam up to 20 pounds gauge pressure is fed into the bottom of the treating cylinder by opening a valve 91 in a pipe 92 connecting steam line 9 with the cylinder. After this steam has served its purpose the cylinder is relieved of it by discharging it to atmosphere when valves 37, 48, and 68 are opened. When the treating cylinder is free of live steam, a vacuum of about 15 inches is created in the cylinder by means of the ejector by opening valves 72, 73, 34, 35, 38, and 75. Then, without reducing this vacuum, the vacuum pump 77 is started to increase the vacuum to 24 inches or as may be required by opening valves 72, and 81. When the vacuum pump is under way, the ejector is cut out. The sap and condensate in the bottom of the cylinder are automatically drained off dur-

ing this operation through a pipe 93 leading to a drum 94.

In boiling timber, such as fir and oak, in preservative oil, the timber is first completely immersed in the preservative in the treating cylinder leaving a small gas space between the top of the cylinder and the preservative. The vacuum pump 77 is then started and the preservative is boiled by the heat from the steam coils 42 in the bottom of the cylinder. The temperature is maintained just a few degrees above the boiling point of water. As the moisture and sap are boiled from the timber the vacuum pump will pull the vapor into the condenser 79, and the condensate can be drawn off and measured. When the steaming or boiling cycle just described has been completed, the wood may be impregnated with preservative as disclosed above.

It will thus be seen that in following my invention, inert gas that otherwise would be wasted is used by simple and inexpensive apparatus to greatly minimize the dangers of fires and explosions in wood preserving plants. In addition to protecting the workers from harm, it also helps preserve valuable natural resources.

According to the provisions of the patent statutes, I have explained the principle and mode of operation of my invention and have illustrated and described what I now consider to be its best embodiment. However, I desire to have it understood that, within the scope of the appended claims, the invention may be practiced otherwise than as specifically illustrated and described.

I claim:

35. Wood-preserving apparatus comprising a treating cylinder for receiving wood to be impregnated with a liquid preservative in the cylinder, a tank for the preservative connected to the cylinder, a source of inert flue gas, a steam-actuated 40 ejector for withdrawing said gas from said source and placing it under pressure, scrubbing and cooling means for the gas connected to the ejector, means connecting said scrubbing and cooling means with said tank, and selective means for 45 connecting the scrubbing and cooling means with said cylinder.

GRANT B. SHIPLEY.
